Franklin Day and William J. Steers, of St. Louis, Mo.

Letters Patent No. 123,860 Dated Augt. 1866.

Design for a Trade Mark.

The schedule referred to in these letters patent and making part of the same
of all whom it may concern:

It is known that we, Franklin Day and William J. Steers, of St. Louis, Mo., have invented a design for a Trade Mark, it being a Brand for "Whiskey Barrels" and we do hereby declare that the following is a full and clear description thereof, reference being had to the accompanying drawing which fully explains the nature of the invention:
The entire head of the barrel is painted a green color. The words "Derby & Day" painted in a curved line concentric with the chimes of the staves around the upper half the head, and the words "St. Louis" in the bottom half of the head complete the whole circle. These words are painted in large capital letters.
The word "Truth" is painted in a straight line across the centre of the head in large capital letters. The word "Truth" above and the word "Whiskey" below the word "Truth" are painted in a small, inter mining, or wavy characters.
Thus the whole lettering on the head of the barrel reads as follows: "Derby & Day St. Louis Truth Whiskey." It is however to be observed that the lettering is done with paint in dark brown or black color.

The name "Derby & Day" for a Trade Mark composed and ar.
